Company, Detroit, Mich., a corporation of
Michigan

Application July 28, 1933, Serial No. 682,588

21 Claims. (Cl. 197—110)

This invention relates to typewriters, and it has to do more particularly with margin stop and release mechanism therefor.

The general object of the invention is to provide an improved typewriter construction.

Another object is to provide an improved margin stop mechanism for limiting the extent of travel of the paper carriage in both directions so that the proper predetermined margin will appear at both the right- and left-hand margins of the paper.

A further object is to provide an improved margin release mechanism which is operable to disable the margin stop mechanism and permit the paper carriage to be moved beyond both its left- and right-hand marginal limits.

Still another object of the invention is to provide an improved margin control mechanism which is accurately timed with the carriage escapement mechanism to positively position the escapement mechanism to start each successive line of typing at exactly the same left-hand marginal position under all speed and other operation conditions.

Additional objects are to provide an improved form of margin stop block adapted to be adjustably supported by and at the forward part of the carriage frame; to provide an adjustable stop block support; to provide improved means operable under the control of margin stop mechanism for preventing operation of the type bar operating keys, the space bar, and the universal bar to an escapement operating extent at the end of a line as determined by the margin stop mechanism; to provide an improved single releasable stop means for controlling both the right- and left-hand marginal positions of the paper carriage; to provide means for positively determining the end of movement of the carriage beyond

its right-hand marginal position after actuation of the margin release mechanism, which means also serves to actuate means for preventing depressing of the type bar operating keys, the space bar and the universal bar to an escapement operating extent; and to provide structure for carrying out the foregoing objects which is simply and durably constructed, and which is composed of parts which are readily accessible and which may be easily and quickly adjusted and operated.

Other objects and advantages will become apparent as this description progresses and by reference to the drawings illustrating one embodiment of the invention wherein:

Figure 1 is a perspective view illustrating the right-hand marginal stop and release mechanism

in normal condition with the typewriter frame, carriage and platen being indicated by dot and dash lines and with the bell ringing means removed;

Fig. 2 is an enlarged, fragmental front elevational view, partially in section, illustrating the right-hand margin block in position preventing further carriage travel and key depression; 5

Fig. 3 is a sectional right side elevational view of the structure shown in Fig. 2 and illustrating key locking and universal bar locking means preventing key depression and universal bar movement when a margin block is in active stop position; 10

Fig. 4 is a fragmental perspective view illustrating the margin blocks, their support and the margin stop detent which is associated with both such blocks; 15

Fig. 5 is a bottom plan view of one of the margin blocks and a portion of its support, certain of the parts being cut away to illustrate the construction more clearly; 20

Fig. 6 is a view similar to Fig. 3, except illustrating an active condition of the universal bar lock with the key locking bail in inoperative condition; 25

Fig. 7 is a fragmentary rear elevational view, partially in section, of the escapement mechanism and illustrating the parts in their respective positions with the escapement mechanism retaining 30 the paper carriage;

Fig. 8 is a view similar to Fig. 7 except illustrating the parts in their respective positions during return movement of the carriage to its left-hand marginal position for the writing of a new line; 35

Fig. 9 is a view similar to Figs. 7 and 8 illustrating the escapement mechanism parts in an out-of-step condition;

Fig. 10 is a detail perspective view, looking from the rear, of the means for finally limiting the carriage in its movement to the left as viewed from the front, and 40

Fig. 11 is a detail section on the line 11—11 of Fig. 3. 45

The typewriter mechanism as a whole includes all those parts requisite in a complete typewriter, inclusive of a frame 1, a traveling paper carriage 2, a case shiftable platen 3, a type bar mechanism embodying type bars 4, and a key-controlled universal bar 5 which actuates ribbon feed and ribbon vibrator mechanisms. Certain of these mechanisms are not necessary for an understanding of this invention, and they have not been illustrated in detail. 50 55

Type bar mechanism

The type bar mechanism (Figs. 1, 3 and 6) includes a plurality of type bars 4 pivotally supported by a type bar segment 6 for swinging movement toward and from the carriage-supported platen 3. Each type bar is operated by a depressible key lever 7 connected to the type bar by a crank 8. A key 9 is mounted on the keyboard end of each key lever 7 for depression of the latter. A frame-carried across shaft 10 supports the cranks 8, and the latter are connected to the respective type bars and key levers by slot-and-pin connections 11 and 12.

The type bar segment 6 is provided with a plurality of slots, one for each type bar, and each type bar is provided with a cam face 13 which moves in the respective segment slot to actuate the universal bar 5 upon the depression of a key 9.

Universal bar mechanism

The universal bar mechanism is adapted to actuate the carriage escapement mechanism, indicated generally at 14 (Fig. 1) as well as ribbon feed and ribbon vibrator mechanisms (not shown).

The forward edge of the universal bar 5 (Figs. 3 and 6) is supported by its stud 300 sliding in the segment 6 and this forward edge of the universal bar moves in a curved slot 20 in the rear of the slotted portion of the type bar segment 6 so that its forward edge will be engaged by the cam face 13 of the type bar 4 as the latter is moved toward printing position.

The universal bar 5 is carried by a frame 21 which is supported at its opposite sides for backward and forward movements by a pair of rock arms 22 and 23 (Figs. 1 and 3) carried by a rock shaft 24 supported by a pair of spaced frame members 25, only one of which is shown in Figs. 3 and 6.

With this arrangement, as the type bar 4 is moved to printing position and its cam face 13 engages the universal bar 5, the universal bar and its frame 21 are moved rearwardly upon the supporting arms 22 and 23 and stud 300. During this movement, a lug 26 on the rear part of the universal bar frame 21 engages a part of the escapement mechanism to effect a carriage escapement action, as will be described more fully hereinafter.

A similar movement of the universal bar is accomplished by a space bar mechanism. More particularly, a space bar 30 (Fig. 1) is supported at the forward part of the machine by a pair of spaced arms 31 fixed to a frame-carried rock shaft 32. This rock shaft supports a rocker arm 33 to which is pivotally connected one end of a lever 34, the opposite end 35 of which is forked for sliding support by a stud 36 carried by one of the frame members 25. The forked end 37 of lever 34 is extended and provided with a lateral projection 38 which is disposed behind a depending extension 39 on the universal bar supporting arm 22. It will be readily seen that, upon depression of the space bar 30, the lever projection 38 is moved forwardly to engage the arm extension 39 and rock the universal bar supporting arms 22 and 23 and the universal bar 5 rearwardly to effect carriage escapement as in the case of operation of the type bar.

Escapement mechanism

The escapement mechanism, under the control of the universal bar 5, serves to cause the paper carriage 2 to space toward the left a predetermined distance each time a key 9 or the space bar 30 is depressed and released in order to present a

new printing position on the platen 3 for the next type impression. The paper carriage is adapted to be urged toward the left by any suitable and well-known spring drum device and, under such urge, the carriage moves to the left a predetermined allotted distance each time the escapement mechanism is actuated.

The escapement mechanism includes an escapement block 40 fixed upon a rock shaft 41 carried by the frame members 25. The escapement block 10 supports an adjustable abutment 42 which is engaged by the universal bar lug 26 in the rearward movement of the universal bar to rock the block 40 in clockwise direction as viewed in Figs. 3 and 6.

The escapement block 40 supports a pair of laterally spaced and diagonally offset escapement dogs 43 and 44. The dog 43 is pivotally supported by block 40 while the dog 44 is fixed to such block. The escapement block dogs 43 and 44 cooperate with an escapement wheel 45 for carriage escapement movement as will now be more fully explained.

A rack 46 is supported by and travels with the paper carriage 2. This rack is constantly in mesh with a pinion 47 mounted upon a shaft 48 supported at its ends by bearing members 49 and 50 (Fig. 3). The shaft 48, as viewed in Fig. 7, is constantly urged clockwise by the rack 46 and the spring-drum-driven paper carriage 2. A drum 51 (Fig. 7) is fixed to shaft 48 and in this drum there are mounted a plurality of pawls 52 which are constantly urged into engagement with the teeth of a ratchet 53 by springs 54.

The ratchet 53 is a fixed part of the escapement wheel 45 which is mounted for free rotation 35 upon the shaft 48 and which controls the escapement of the carriage. Normally, as viewed in Fig. 7, the drum 51 is urged clockwise by the shaft 48, the pawls 52, at the same time, engaging the ratchet 53 to urge the latter and the escapement wheel 45 clockwise to engage its tooth 55, for example, with the movable escapement dog 43. The escapement dog 43 is normally urged away from its supporting block 40 by a spring 57; however, in the normal position of the escapement mechanism, as illustrated in Fig. 7, the urge of the carriage is sufficient to move the escapement wheel 45 and the dog 43 to compress the spring 57 so that the dog 43 limits against the escapement block 40, thereby providing a positive stop for the escapement mechanism and the carriage 2.

Rearward or clockwise movement of the escapement block 40 shifts the movable dog 43 out of engagement with the escapement wheel tooth 55 and the fixed dog 44 into the path of the tooth 55, thereby permitting the escapement wheel 45 to move clockwise slightly and limit against the fixed dog 44. This action takes place at the end of the down stroke of a key 9 and after the type bar 4 has moved into printing position, and it permits a partial escapement movement of the drum 51 and carriage 2.

The universal bar 5 is moved forwardly under the urge of a spring 58 (Figs. 3 and 6) acting on the depending extension 39 of arm 22 upon release of the space bar 30 or key 9, as the case may be. As this movement takes place, the escapement block 40 is rocked forwardly, or counterclockwise as viewed in Fig. 3, by a spring 59 acting on arm 60 carried by the escapement block shaft 41 so that the fixed dog 44 is moved out of engagement with the tooth 55 and the movable dog 43 is moved into the path of the next succeeding tooth 61. (It will be understood that all 75

of the teeth of the escapement wheel 45 are identical and that they are given different numeral designations herein in order to facilitate description of the escapement action.) This action permits the escapement wheel 45 to be moved further clockwise under the urge of the carriage 2, and to an extent sufficient to limit the tooth 61 against the movable dog 43 to complete one full escapement movement. It is to be understood that the dog 43 will rock counterclockwise until limited by the block 40.

This escapement action is repeated upon each depression of a key or the space bar. When the end of a line is reached and the carriage is returned to its left-hand marginal position, a stop dog 62 prevents movement of the then-floating escapement wheel 45 out of its proper escapement relation. More particularly, return movement of the carriage moves the shaft 48 and drum 51 with its pawls 52 in a counterclockwise direction as viewed from the rear of the machine. During this movement, the parts assume the position illustrated in Fig. 8 wherein the escapement wheel 45 is moved to seat its tooth 63, for example, upon the shoulder 64 of the stop dog 62 and the escapement wheel tooth 55 is slightly released counterclockwise from its normal limiting position shown in Fig. 7, so that the escapement wheel is maintained in a predetermined position against the shoulder 64 by the dog 43 being urged clockwise by the spring 57. When the carriage is fully returned to its right-hand position, as predetermined by margin stop mechanism, and is then released, the drum 51 and pawls 52 are permitted to rotate slightly clockwise to again engage the proper tooth of ratchet 53 and return the parts to the normal position of Fig. 7 with tooth 55 of the escapement wheel 45 limiting against the movable dog 43 which is, in turn, seated against the escapement block 40.

The left-hand margin stop mechanism is so set that the pawls 52 are rotated a slight distance beyond the particular ratchet teeth 65 to be engaged at the time the margin stop mechanism becomes effective to stop the return movement of the carriage. This clearance or lead movement of the pawls 52 may be approximately .025", or less than the pitch of one tooth space on the ratchet 53, for efficient operation of the structure shown. With this arrangement, for any particular left-hand marginal position of the carriage 2, the proper tooth of the escapement wheel 45 will always limit against the escapement dog 43 when the carriage is returned to its left-hand marginal position and each line of typing will always begin at the same marginal position and thereby retain perfect vertical alignment. Further, the escapement pawls 52 will always pick up the proper teeth of ratchet 53 for the foregoing return movement of the escapement mechanism to properly position the paper carriage in its left-hand marginal position. If the foregoing relationship between the parts of the escapement mechanism is changed or interfered with in the operation of the machine, the pawls 52 will not engage and pick up the proper ratchet teeth with the result that the carriage will assume an improper left-hand marginal position. It will, therefore, be apparent that a definite timed operating relationship exists between the escapement mechanism and the margin stop mechanism.

Margin stop mechanism

The margin stop mechanism is provided to adjustably limit the travel of the paper carriage in

both directions in order that the proper and desired margin will appear on both the left- and right-hand edges of the paper to be typed upon.

The margin stop mechanism includes right- and left-hand margin blocks 70 and 71 which are mounted on the forward part of the carriage 2 so as to be readily and quickly accessible for adjustment by the machine operator. These blocks are slidably supported upon the carriage 2 by a rack bar 73.

The margin blocks 70, 71 are similar in construction, except that they are reversed, and only one of the same will be described in detail. The margin block includes a U-shaped body member 74 which slidably embraces the supporting rack bar 73. A dog 75, which is pivotally mounted at 76 in the open end portion of the block body 74, is provided with a depending head portion having a plurality of (preferably, but not necessarily, three) teeth 77 adapted to mesh with the teeth 78 of the rack 73. The dog teeth 77 are constantly urged into mesh with the rack teeth by a leaf spring 79, which has one end thereof secured to the dog 75 at 80 on the side of the dog pivot 76 adjacent the teeth 77. The other and free end of the spring 79 is bowed downwardly so that it projects downwardly across the dog pivot 76 to a point where it is spaced from the U-base of the block body 74 a distance less than the width of rack 73. When the block is mounted upon the rack 73, the spring 79 is, therefore, placed under tension to urge the block dog 75 clockwise about its supporting pivot 76 to yieldably engage its teeth 77 with the rack teeth 78.

The dog 75 is provided with a thumb knob 81 and one of the U-arms of the block body is provided with a finger lug 82 located adjacent and substantially parallel to, but slightly spaced from, the thumb knob 81. Normally, the block is locked against movement along its supporting rack 73 by the toothed engagement between the dog 75 and rack 73; however, when it is desired to slide or adjust the block along the supporting rack, the finger members 81, 82 may be grasped to press the knob 81 against the lug 82 thereby rotating the teeth of the dog 75 away from and out of contact with the supporting rack. With the parts held in this position, the margin block may be moved along the rack to the desired position and the finger hold released at which time the teeth 77 of the dog 75 will again engage the rack to position the block for stopping the carriage.

Each margin block is disposed in horizontal position on the rack bar 73 and the underside of the body thereof is provided with a depending lug 83 which is disposed in the path of a frame-carried stop member 84. When the carriage 2 is moved to the right by the operator, the lug 83 on block 71 engages the adjacent edge of the stop member 84 and limits further movement of the carriage in that direction. When the carriage is tabulated or spaced to the left by the depression of keys, or the space bar, or otherwise, the lug 83 of the right-hand marginal block 70 eventually engages the opposite side of the stop member 84 and limits the movement of the carriage in its left-hand travel direction. The foregoing stop means determines both the right- and left-hand marginal positions of the carriage. The marginal position may be readily and quickly varied by changing the position of the margin blocks along the supporting rack 73.

The stop member 84, preferably, forms a part of a lever 85. This lever 85 is provided with an elongated slot 86 intermediate its ends and it is 75

5 pivotally and reciprocably supported upon a cross frame member 86 by a screw stud 87 which passes through such slot. A coil spring 89 is connected near the end of the stop lever 85 opposite the stop member 84 and also to a fixed stud 89' on the downwardly projecting extension of the cross frame member 86. In this way, the stop member 84 is urged upward into and yieldably held in its 10 normal margin stop position in the path of the stop lugs 83 on the margin blocks 70 and 71.

10 *Margin release mechanism*

15 The margin release mechanism is provided to enable the operator to disable the margin stop mechanism for movement of the paper carriage beyond either of its predetermined marginal positions. The margin release mechanism is arranged to swing the lever 85 counterclockwise (Fig. 2) to move the stop member 84 downward 20 out of the path of the margin block lugs 83 so that the carriage may be moved in either direction beyond the position normally determined by the margin blocks. This action is accomplished by the actuation of a margin release key 90.

25 The margin release key 90 (Figs. 3 and 6) is supported and guided for vertical reciprocatory movement by a frame-carried cross plate (not shown) and it is pivotally connected to one end of a lever 92 pivotally supported by a frame-carried stud 93. The other end of the lever 92 is pivotally connected at 94 to the lower offset end portion of a vertical lever 95, the upper end portion of which is provided with an elongated slot 96 (Fig. 2) for vertical slide support connection with a frame-carried stud 97. The extreme upper end of lever 95 is shaped to form an abutment 98 upon which the underside of the right-hand end 99 of the stop lever 85 seats to normally hold that end of the stop lever in a predetermined position locating the stop member 84 in the path of the margin block lugs 83.

30 The stop member 84 may be released or disabled by depressing the release key 90, thereby swinging the lever 92 to elevate the lever 95 and, in turn, elevate the abutment or right-hand end 45 of the stop lever 85 to lower its other end and the stop member 84 out of the path of the margin block abutments 83.

35 It will be seen from the foregoing that a single frame-carried stop member serves to position the carriage in both its right-hand and left-hand marginal positions; and that a single release key is operable to disable this stop device to permit movement of the carriage to the full 50 limit of its travel in both directions. That is to say, to move the carriage 2 either to the right or left after the respective margin block engages the stop member 84, it is only necessary to depress the margin release key 90 to lower the stop member 84 and then move the carriage manually 55 in the desired direction.

60 As the carriage moves beyond the stop member 84 in either direction, the spring 89 returns the stop lever 85 and its stop 84 to their normal 65 positions of Fig. 1 and it also acts through lever 85 to restore the release key 90 and its connections to their normal positions. Although, at this time, the stop member 84 is again disposed in the path of the respective margin block, it is 70 disabled by the respective margin block in the return movement of the carriage to within its normal margin limits as follows:

75 The stop lugs 83 on both margin blocks are rigidly braced upon the margin block body 74 by web portions constituting cam members 100.

These cam members are aligned with the stop member 84 and they taper gradually upward from the lower edge of the margin block lugs 83 to the margin block body 74 so that they readily engage and depress the stop member 84 as they pass thereover on the return. That is to say, for example, in movement of the carriage to the left from a right-hand position where in its margin block 71 is disposed to the right of the stop member 84, the cam surface 100 of the margin block 71 engages the top of the stop member 84 and depresses it out of the path of the block stop 83 until the margin block moves therebeyond. This same camming action takes place with respect to the margin block 70 in movement of the carriage from a left-hand position wherein its margin block 70 is disposed to the left of the stop member 84. In other words, the margin release key 90 must be manually depressed to permit the carriage to move to the right or left beyond its 10 normal marginal positions, but the cam members 100 on the margin blocks 70, 71 disable the stop member 84 when the carriage is returned in either direction to within its normal marginal limits.

20 The right-hand margin block 70 also actuates 25 a signal which warns the operator that the right-hand marginal limit is being closely approached. In the tabulation or spacing of the carriage to the left, the lug 83 on the margin block 70 engages the cam face 101 of a pass-by pawl 102 a few 30 spaces in advance of its point of engagement with the stop member 84. Pass-by pawl 102 is pivotally supported upon one end of a bell-hammer lever 103 which is, in turn, pivotally supported at 104 by the frame cross piece 86. The pawl end 35 of lever 103 is provided with a lateral lug 105 disposed behind the pawl 102 to prevent counterclockwise rotation of the pawl 102 when it is engaged by the margin block lug 83; wherefore, as the margin block lug 83 moves over the cam surface of this pawl, the pawl end of lever 103 is 40 depressed, thereby elevating its other end which supports a bell-hammer 106.

45 Movement of the margin block 70 beyond the pawl 102 releases the lever 103 and permits its hammer 106 to fall and strike a bell 107. The bell lever 103 is held normally with its hammer end downward adjacent the bell 107 by a spring 108 connected thereto adjacent the hammer and to a fixed frame-carried member (not shown). 50 It will, therefore, be seen that the lever 103 is rotated counterclockwise by the margin block against the urge of spring 108 so that as the margin block moves beyond the cam surface of the pawl 102 the spring will return the lever 103 and hammer 106 in clockwise direction to their normal 55 positions (Fig. 2) with sufficient force to cause the hammer 106 to strike the bell 107 and give the desired warning. This warning signal is given a sufficient time ahead of engagement of the margin block 70 with the margin stop 84 to permit the operator to gauge the number of 60 letter spaces available in that particular line before the carriage is finally stopped by the margin stop mechanism.

65 The bell lever or pass-by pawl 102 is mounted to partially rotate in a clockwise direction so that, as the carriage is returned to its normal right-hand position, the stop member 83 of margin block 70 strikes and moves the pawl 102 clockwise out of the path of the margin block without interfering with the position of the bell hammer lever 103. The underside of the pawl 102 is slightly enlarged to provide sufficient weight 70 thereat to insure that the pawl will swing back 75

to its normal upright position of Fig. 2 after the margin block has passed thereover as just stated.

When the margin block 70 engages the stop member 84, further full depression of the keys 9 is prevented. Otherwise, depression of the keys with the carriage incapable of further movement would result in several letters being printed one on top of the other.

To positively insure against key depression at the end of a line under all conditions of operation, including high speed operation or otherwise, this invention contemplates the provision of dual locking means for both the keys 9 and the universal bar 5. This means is controlled by margin stop mechanism when the end of a line, as determined by a margin stop, is reached.

Key lock

The key lock includes a bail 110 disposed crosswise of the machine beneath the type bar and space bar levers 7 and 31, respectively. This bar is provided with a longitudinal rib 111 adapted to give strength thereto and it is also provided at its opposite ends with laterally turned ears 112 which are pivotally connected to the opposite sides 114 of the machine frame by pins 113 (Figs. 1 and 3). The upper edge of this bar is turned over to provide a flat surface adapted to be engaged under certain conditions by the depending arms 115 and 116 on the key and space bar levers 7 and 31, respectively, when the keys 9 and space bar 30 are depressed.

The key lock bail 110 is normally held in position out of the path of the key lever and space bar arms 115, 116; however, upon engagement of the margin block 70 with the stop member 84, this bail 110 is rotated clockwise to position its upper edge beneath the key lever and space bar arms to prevent depression of the key and space bar levers 7, 31 to an extent sufficient to move the type bars 4 to printing position by the key levers 7, or to cause a mis-operation of the escapement by depression of the space bar 30. Blocking a depression of the key lever 7 and space bar arms 31 prevents actuation of the universal bar and the consequent escapement movement of the paper carriage.

Specifically, as shown in the drawings, the right-hand end of the stop lever 85 (Fig. 2) is provided with a lateral pin 117 which is received within the forked end 118 of a crank 119. Crank 119 is pivotally supported by the stud 97 that is received in the slot 96 of the upright release lever 95. A downwardly extending lever 120 has its upper end pivotally connected to the crank 119 and the lower end of this lever is connected to the right-hand lateral ear 112 of the key lock bail 110 by a stud and slot connection 121, 122. The stud 121 is constantly urged into and yieldingly held in the lower end of the slot 122 by a spring 123 so that the key lock bail 110 is held in its released normal position of Fig. 1 and it will be moved immediately to a key locking position in response to downward movement of the vertical lever 120.

Engagement of the right-hand margin stop 70 with the stop member 84 moves the stop lever 85 to the left, this being permitted by the stud and slot support 81, 88 of this lever. As the stop lever is thus moved, the crank 119 is moved counterclockwise to shift the lever 120 downwardly and, in turn, rock the key locking bail 110 clockwise to the position of Fig. 3 wherein its upper edge is disposed directly beneath the

arms 115, 116 on the key levers 7 and space bar levers 31, respectively. Depression of the key or space bar levers to an escapement or printing extent is thus prevented.

The stop member 84 and the margin block 70 are preferably, so relatively positioned that only a single escapement action of the escapement mechanism is necessary to move the key locking bail 110 into position to block full depression of the keys and space bar. That particular escapement movement just previous to engagement of the margin block with the stop 84 positions the margin block 70 at such a point that there is but a very slight clearance between it and the stop 84. In other words, these parts should be so related that when the carriage and its block 70 move during the next succeeding escapement operation, the block 70 shifts the stop lever 85 to the left substantially a full escapement movement. For the purpose of this description, it may be assumed that the length of each escapement movement is .100"; but it is to be understood that the length of this movement may be varied according to the size, character, etc. of the type employed and other conditions of use.

When using an escapement movement of .100", the slot 88 in the stop lever 85 is of approximately .125" in length so that there is approximately .025" slot clearance after the movement of the stop lever 85, and this insures that this movement may be accomplished without interference. It is to be further understood that whatever the length of the escapement movement may be, the length of slot 88 is, preferably always such that this clearance of .025" is provided for after a full escapement movement of the carriage and stop lever 85 as just stated. To insure that the desired relationship between the margin blocks 70 and stop member 84 will be maintained, the carriage rack is supported for adjustment longitudinally of the carriage, as follows:

Rack 73 has its opposite ends received within the open ends of similarly-constructed U-shaped brackets 130, the closed ends of which support adjustment screws 131. The opposite ends of the rack 73 are provided with elongated slots 132, and screw bolts 133 pass through the carriage frame member 134, the U-shaped supports 130 and the slotted rack openings 132 to receive a nut 50 135 for securely mounting the rack and its supports upon the forward part of the carriage frame. The rack 73 may be adjusted relative to the stop member 84 by loosening one of the screws 131 and tightening the other to shift the rack longitudinally to the desired extent. Lock nuts 136 are mounted upon the projecting portions of the screws 131 to maintain the predetermined adjustment of the rack as well as to shield the screws 131 against accidental movement. By thus adjusting the rack 73, the margin block 70 can be accurately positioned to cause its stop lug 83 to practically immediately pick up and actuate the stop lever 85 and the key locking bail 110 to a full escapement extent when the margin stop mechanism becomes effective.

The proper timing of the margin stop mechanism is quite essential to the end of preventing any key or space bar depression which would tend to disturb that predetermined step-by-step relationship of the escapement mechanism necessary for positioning the carriage in its proper left-hand marginal position as hereinabove more particularly set forth.

Universal bar lock

The universal bar lock prevents movement of the universal bar 5 to effect an escapement action after engagement of the margin block 70 with 5 the margin stop 84 should the key locking bail 110 fail to prevent a subsequent key depression.

Although the key locking bail 110 normally prevents key depression and escapement action after 10 the right-hand margin block 70 engages the margin stop and moves a full escapement distance, an extremely rapid operator may be able 15 to depress a second key after a first key has been depressed to actuate the margin stop and before the key locking bail 110 has been moved into its key-blocking position. Depression of the first 20 key results in a full carriage escapement movement in the manner already explained, and the depression of a second key under the above conditions causes the proper type bar to be moved 25 to printing position so that a print by the second key depression is made on the paper but not necessarily in the proper position. Its position may vary up to .025" out of the proper place due to the extra .025" movement of the stop lever 30 85. This condition, however, causes an incomplete escapement so that when the carriage is returned to its left-hand marginal position the next printed line will start one space out of its proper marginal position, namely, one space to 35 the right of its left-hand marginal position.

More particularly, the full escapement action 40 under the control of the first key which actuated the margin stop mechanism will shift the paper carriage 2 and the stop lever 85 one full space to the left. Since the slot 88 in the stop lever 85 is long enough to accommodate only one full escapement movement plus .025", the carriage 2 can travel only .025", or an incomplete escapement distance, upon actuation of a key following 45 the operation of the margin stop mechanism.

Therefore, when a second key is depressed 50 before the first key (the one which operates the margin stop mechanism) is restored and before a sufficient escapement movement of the carriage 55 2, takes place to set the key locking bail 110 to prevent further key depression, the universal bar 5 is again actuated by the second key to effect an escapement action. However, since the carriage 2 can move only .025" to the left, the escapement mechanism assumes only a partial escapement position such, for example, as that illustrated in the "out-of-step" condition of Fig. 9.

In this partial escapement position of the carriage and escapement mechanism, the carriage 60 improperly limits against the margin stop 84 rather than against the escapement dog 43. That is to say, in this partial escapement action, the escapement wheel tooth 55, for example, which should be engaged with and seated upon the dog 65 43, as shown in Fig. 7, is moved clockwise past the dog 43, thereby positioning the ratchet 53 so that the drum-carried pawls 52 will pick up, for example, the ratchet tooth 66 instead of the proper ratchet tooth 65 when the carriage is returned 70 to the left and released. At this time, since the escapement wheel tooth 55 has moved clockwise beyond the dog 43, the drum 51 under the urge of the carriage 2 will be rotated clockwise to engage the similar and next succeeding escapement wheel tooth 61 instead of the proper tooth 55 with the dog 43. The carriage will thereby be returned to a position wherein the next printed line will begin one space to the right of the 75 intended left-hand marginal position.

The universal bar lock (Figs. 3 and 6) prevents any escapement action after the margin stop is engaged so that the escapement mechanism, when an end of a line is reached, always assumes the proper in-step condition illustrated in Fig. 7. 5

The universal bar lock is controlled by the margin stop mechanism and is inter-connected with the control parts of the key locking bail 110 in such a way that it is actuated slightly in advance of the keylocking bail. The universal bar lock is 10 so timed that it, preferably, assumes an operable locking condition almost immediately after engagement of the margin block 70 with the stop 84 and prior to the completion of the margin block movement or movement of the key locking bail 15 110 to its operative key stop position of Fig. 3.

The universal bar lock includes a crank 140 pivotally supported by a frame-carried stud 141. One arm of this crank is pivotally connected to the adjacent vertical lever 120 which is also connected to and operates the key locking bail 110 as already described. The other arm of crank 140 is pivotally connected to one end of a rearwardly and horizontally extending lever 142 which has its other end pivotally connected to a 25 rock arm 143 secured to a right-angularly-disposed and frame-carried rock shaft 144.

The rock shaft 144 adjacent its end opposite the arm 143, supports a rearwardly extending hook arm 145. The hook end 147 of this arm 30 145 is adapted to extend over and rearwardly behind a lateral pin 146 carried by one of the rock arms 23 which support the rear portion of the universal bar frame 21.

When the parts are in their normal positions 35 of Fig. 1, the vertical lever 120 is held raised by the spring 89 thereby holding the universal bar lock hook 147 raised out of the path of the universal bar lock pin 146. As the margin block 70 engages the margin stop 84 and shifts the stop 40 lever 85 to the left, the lever 120 is shifted downwardly by the counterclockwise movement of the crank 119 to, in turn, rock the universal bar lock crank 140 in counterclockwise direction, as viewed in Figs. 3 and 6. This rocking movement of the 45 crank 140 shifts the lever 142 forwardly and moves the hook arm 145 downwardly with its hook end 147 behind and in the path of the universal bar locking pin 146. The downward movement of the vertical lever 120 is permitted, even though an arm 116 of a key may be in position to prevent movement of the key locking bail 110 clockwise to its key stop position (Figs. 3 and 11), by the yieldable slot and pin connection 121, 122 between the key locking bail ear 112 and the lever 55 120. That is to say, while the spring 123 normally holds the pin 121 of this connection in the lower part of the slot for operation of both the locking bail 110 and lock arm 145, this spring will yield and permit depression of the lever 120 60 to actuate the lock arm 145 while the lock bail 110 remains stationary, as illustrated in Fig. 6.

The lock arm 145 is so positioned upon its shaft 65 144 that, upon a very slight downward movement of the lever 120, it assumes a position preventing rearward movement of the universal bar to an escapement extent. This lock becomes effective slightly in advance of movement of the key locking bail 110 to its full key stop position. Movement of arm 145 is so timed that, even though a key 9 may be depressed after the margin stop is engaged, the universal bar 5 cannot be actuated to effect an escapement action. Also, the type bars 4 cannot be moved into printing 70 75

position because the locked and then stationary universal bar 5 blocks such movement.

Final carriage stop

Following engagement of the margin block 70 with margin stop 84 and depression of the margin release key 90, the carriage may be moved to the left a limited number of letter space movements. This movement is positively stopped by a final stop mechanism which is engaged and actuated by the carriage. This final stop mechanism not only nonreleasably and positively regulates the end of a line of movement of the carriage 2 to the left after releasing the right-hand margin stop, but it also actuates the key lock and universal bar lock mechanisms hereinbefore described, positively preventing actuation of keys 9, and space bar 31, at the extreme end of the movement of the carriage to the left.

The final carriage stop mechanism (Figs. 2, 3 and 10) includes a slotted side plate 200 supported on the underside of the front carriage rail 201 by shouldered screws 202. The slide plate 200 normally floats on the carriage rail and it is provided at its right hand end, as viewed from the front of the machine, with a downwardly projecting ear 203 adapted for engagement with a horizontal and rearwardly projecting stud 204 carried by the stop lever 85. The left end of the slide plate 200 is turned horizontally rearward and then upward to provide an upstanding arm 205 which is disposed in the path of the right side carriage end frame member 206.

As the carriage reaches its left-hand movement limit beyond the margin block 70, the carriage frame member 206 engages the slide plate arm 205 and shifts the slide plate 200 to the left, as viewed in Fig. 2, the extent of movement of such plate being limited by the ends of the slide plate slots 207 engaging the screws 202. The slide plate ear 203 is normally located closely adjacent the stop lever stud 204, and, as the carriage engages and moves the slide plate 200, to the left, the slide plate 200 picks up and shifts the stop lever 85 to the left. These parts are so related that, in the foregoing operation, the stop lever 85 is shifted, preferably, one full escapement step to the left.

This shift movement of the stop lever 85 rocks the bell crank 119 counterclockwise to depress the vertical lever 120 and rock the key locking bail 110 to its Fig. 3 position wherein depression of the keys 9 and space bar 31 is prevented. This downward movement of the lever 120 also serves to rock the hook arm 145 of the universal bar lock thereby blocking rearward movement of the universal bar 21 and, in turn, depression of the keys 9 and space bar 31 as hereinbefore more fully described.

The number of letter spaces or escapement movements permissible after the margin block 70 engages the margin stop 84 and upon actuation of the release key 90 is determined by the position of the margin block 70 on the rock bar 73.

Operation

The left-hand marginal position of the carriage may be located by adjusting the margin block 71 to the desired position upon its rack 73. This position may be determined by a scale (not shown) associated with the carriage frame above the rack 73 where it will be constantly within the vision of the operator. To facilitate setting of the margin block 71 to a predetermined marginal position indicated upon the platen-carried paper, scale means (not shown) corresponding to

the margin block scale means may be associated with auxiliary pressure roll structure 210 (Figs. 3 and 6) so that this margin block may be set along its scale to agree with a position on the paper as indicated by the scale immediately adjacent the paper. Both of these scale means may be so located as to be constantly within the vision of the operator at all times.

The right-hand marginal position of the carriage is likewise determined by similarly adjusting the margin block 70.

Further operation of the structure shown will be readily understood from the foregoing description.

It is to be understood that the structure shown is for purposes of illustration only and that variations may be made therein without departing from the spirit and scope of the invention as defined by the appended claims.

I claim:

1. In a typewriter, a movable platen carriage, depressible key levers for operating type bars, a universal bar actuated by the type bars, means for normally limiting movement of said carriage to the left and to the right to predetermine right- and left-hand marginal positions of said carriage, means for locking said key levers against depression, separate means for locking said universal bar against movement, and means including a single train of connections for actuating both said locking means by said carriage movement limiting means as said carriage moves to its right-hand marginal position.

2. In a typewriter having a frame, a carriage, type bars, depressible keys for moving said type bars to printing position, a universal bar actuated by said type bars, and escapement mechanism actuated by said universal bar, the combination of margin stop means carried by said carriage, a margin stop member carried by said frame and adapted to be engaged by said carriage-carried stop means, and separately operable locking means actuated by said stop member through a single-train of connections as it is engaged by said carriage-carried stop means for separately preventing depression of said keys to an extent sufficient to move said type bars to printing position and preventing movement of said universal bar to an extent sufficient to actuate said escapement mechanism.

3. In a typewriter having a frame, a carriage, type bars, depressible keys for moving said type bars to printing position, a universal bar actuated by said type bars, and escapement mechanism actuated by said universal bar, the combination of margin stop means carried by said carriage, a margin stop member carried by said frame and adapted to be engaged by said carriage-carried stop means, key locking means for preventing depression of said keys to an extent sufficient to move said type bars to printing position, universal bar locking means for preventing movement of said universal bar to an extent sufficient to actuate said escapement mechanism, and connections between said frame-carried stop member and both said key locking and universal bar locking means for actuating the latter as said frame carried stop member is engaged by said carriage-carried stop means.

4. In a typewriter having a frame, a carriage mounted for movement on said frame, type bars, keys for moving said type bars, a universal bar actuated by said type bars, and escapement mechanism actuated by said universal bar, the combination of a margin block adjustably mounted

- on said carriage, a stop lever slidably mounted on said frame and having a stop member thereon adapted to be engaged by said margin block at the end of a typed line to shift said stop lever in 5 the direction of movement of said carriage, a member swingably mounted beneath said keys and adapted in one position thereof to be engaged by said keys to block operative depression of the latter, connections between said stop lever and said key blocking member, another member 10 swingably mounted adjacent said universal bar and adapted in one position to engage the latter and block movement thereof, and means connecting said universal bar blocking member to 15 first-named connections for actuation of both said blocking members to their blocking position as said margin block engages said stop member and shifts said stop lever.
5. In a typewriter having a frame, a carriage 20 mounted for movement on said frame, type bars, keys for moving said type bars, a universal bar actuated by said type bars, and escapement mechanism actuated by said universal bar, the combination of a margin block mounted on said carriage, a stop lever mounted on said frame for longitudinal shift movement equal at least to the length of one complete escapement movement of said carriage, a stop element on said stop lever disposed normally in the path of said margin 25 block and adapted to be engaged by said margin block to shift said stop lever approximately one full escapement distance, key locking means disposed normally in an inactive position, universal bar locking means disposed normally in an inactive 30 position, and means interconnecting said two locking means and said stop lever with each other and arranged to move said two locking means to active key and universal bar locking position at least by the time said lever has completed its said complete escapement distance 35 movement.
6. In a typewriter, the combination of a carriage, type bars, keys for operating said type bars, a universal bar actuated by said type bars, 40 escapement mechanism operated by said universal bar, a margin block on said carriage, a slidably mounted stop member adapted to be engaged by said margin block at the end of a typed line, a normally inactive key lock, a normally inactive universal bar lock, connections between 45 said stop member and said key lock including a lever for moving said key lock to a position to block depression of said keys upon slide movement of said stop member as it is engaged by said margin block, and connections between said lever and said universal bar lock for also moving the latter to a position wherein it blocks movement of said universal bar.
7. In a typewriter, the combination of a carriage, type bars, keys for operating said type bars, a universal bar actuated by said type bars, escapement mechanism operated by said universal bar, a margin block on said carriage, a slidably mounted stop member adapted to be engaged by said margin block at the end of a typed line, a normally inactive key lock, a normally inactive universal bar lock, connections between 55 said stop member and said key lock including a lever for moving said key lock to a position to block depression of said keys upon slide movement of said stop member as it is engaged by said margin block, and connections between said lever and said universal bar lock for also moving the latter to a position wherein it blocks movement of said universal bar, said lever having a 60

yieldable connection with said key lock permitting movement of said lever to actuate said universal bar lock should movement of said key lock be blocked.

8. In a typewriter having a frame, a platen carriage movably supported thereby, type bars operated by key levers, a universal bar actuated by said type bars, and escapement mechanism operated by said universal bar, the combination of a stop abutment on said carriage, a stop lever shiftable to a limited extent on said frame and having a stop element on one end disposed in the path of said stop abutment, a member movable to a position to block depression of said key levers, another member movable to a position to block movement of said universal bar to an extent sufficient to actuate said escapement mechanism, a bell crank connected to said stop lever opposite said stop element, a connection between said bell crank and said key lever blocking member, another bell crank connected to said connection, and a connection between said second bell crank and said universal bar blocking member, whereby both said blocking members are moved to their blocking positions as said stop lever is shifted by engagement of said stop abutment with said stop member.
9. In a typewriter having a frame, a carriage, type bars, depressible key levers for operating said type bars, and a universal bar operated by said type bars, the combination of a margin block mounted on said carriage and having a stop element thereon, a stop lever mounted on said frame for longitudinal shift movement and having a stop member thereon adapted to be engaged by said stop element, a locking bail swingably mounted beneath said key levers for movement from a normally inactive to an active position preventing operative depression of said key levers, a separate locking device associated with said universal bar to prevent movement of the latter, and means connecting said locking bail and locking device with said stop member lever including a bell crank connected to said lever, a reciprocable lever connected to said bell crank, a link element between said reciprocable lever and said lock device and a slot-and-pin connection between said reciprocable lever and said locking bail permitting movement of said reciprocable lever to actuate said lock device independently of said locking bail.
10. In a typewriter having a frame, a carriage, type bars, depressible key levers for operating said type bars, and a universal bar operated by said type bars, the combination of a margin block mounted on said carriage and having a stop element thereon, a stop lever mounted on said frame for rotary swing and longitudinal shift movements and having a stop member thereon adapted to be engaged by said stop element, a locking bail swingably mounted beneath said key levers for movement from a normally inactive to an active position preventing operative depression of said key levers, a lock device associated with said universal bar and adapted to prevent movement of the latter, and means connecting said locking bail and lock device and said stop member lever including a bell crank connected to said lever, a reciprocable lever connected to said bell crank, and a yieldable connection between said reciprocable lever and said locking bail permitting actuation of said lock device by said stop member through said connecting means independently of said locking bail.
11. In a typewriter having a frame and a 75

- platen-supporting carriage movably mounted thereon, margin stop means which includes a pair of margin blocks mounted on said carriage for adjustment longitudinally thereof and each 5 having a stop member thereon, a single reciprocal stop element mounted on said frame, means for yieldably urging said reciprocal stop element into a raised position to be engaged by both said margin block stop members to limit 10 movement of said carriage in one direction and determine one marginal position thereof, manual means for lowering said reciprocal stop element out of the path of said margin block stop members to permit movement of said carriage 15 beyond either of its predetermined marginal limits, and cam means on both said margin blocks for bracing said stop members and for engaging and depressing said stop element out of the path of said margin blocks without disturbing said 20 manual means during movement of the carriage and margin blocks from positions beyond the marginal limit normally predetermined by said margin blocks to a position normally within said marginal limits.
- 25 12. In a typewriter having a platen carriage, type bars, depressible keys for operating said type bars, a universal bar actuated by said type bars and escapement mechanism actuated through the operation of said universal bar, the 30 combination of means for positively stopping said carriage in a selected right hand marginal position, means for releasing said stop means to permit movement of said carriage beyond said selected marginal position, means beyond said stop 35 means for stopping said carriage in a final stop position beyond said selected marginal position, and means actuated by both said stop means for preventing depression movement of said keys and independently preventing escapement-operation- 40 movement of said universal bar.
13. In a typewriter having a frame, a platen carriage thereon, and escapement mechanism, means for preventing actuation of the escapement mechanism when the carriage reaches the 45 end of its movement in one direction, said means including a plate mounted on the frame for limited longitudinal shift movement and adapted to be engaged by the carriage when the latter reaches the end of its movement, a lever mounted on the frame for limited longitudinal shift 50 movement and adapted to be engaged by said plate in the shift movement of the latter by the carriage, locking means movable to a position to block actuation of the escapement mechanism, 55 and connections between said locking means and said lever whereby said locking means is moved to its blocking position upon shift movement of said plate by the carriage.
14. In a typewriter having a frame, a platen 60 carriage thereon, a universal bar and escapement mechanism operated thereby, means for locking the universal bar against movement when the limit of movement of the carriage in one direction is reached, said means including a plate 65 mounted on the frame for shift movement and adapted to be engaged and shifted by the carriage as it moves to its movement limit, a lever mounted on the frame for shift movement and adapted to be engaged and shifted by said plate, normally 70 inactive means for locking the universal bar against movement, and means connecting said lever and locking means for movement of the latter to locking position upon shift movement of said plate by the carriage.
- 75 15. In a typewriter having a frame, a platen carriage thereon, depressible type bar operating keys, a universal bar operated by depression of the keys and escapement mechanism operated by the universal bar, means for locking the keys against operative depression movement when the 5 limit of movement of the carriage in one direction is reached, said means including a plate mounted on the frame for shift movement adapted to be engaged and shifted by the carriage as it moves to its movement limit, a lever mounted on the frame for shift movement and adapted to be engaged and shifted by said plate, a normally inactive device for blocking movement of the keys, and means connecting said lever and device for movement of the latter to key blocking position upon shift movement of said plate by the carriage.
16. In a typewriter having a frame, a platen carriage thereon, depressible type bar operating keys, a universal bar operable by depression of the keys, and escapement mechanism operated by the universal bar, means for preventing escapement movement of the carriage when the limit of its movement in one direction is reached, said means including a plate member mounted 20 on the frame for limited shift movement and adapted to be engaged and shifted by the carriage as it moves to its movement limit position, a lever mounted on the frame for limited shift movement and adapted to be engaged and shifted by said plate, normally inactive means for blocking movement of the universal bar, normally inactive means for blocking depression of the keys, and means interconnecting both said locking means and said lever for movement of 25 said locking means to operative locking position upon shift movement of said plate by the carriage.
17. In a typewriter having a frame, a platen carriage thereon, depressible type bar operating 30 keys, a universal bar operated by the keys, and escapement mechanism operated by the universal bar, a margin stop mechanism including a stop member on the carriage adjustable for limiting movement of the carriage in one direction to a 35 selected marginal position, a stop member on the frame having limited shift movement and adapted to be engaged by the carriage stop member for limiting the carriage to said selected marginal position, locking means associated with 40 the keys and universal bar and normally inactive, connections between said locking means and said frame stop member for moving said locking means to locking position upon engagement of said stop members, means for releasing said frame stop 45 member to permit movement of the carriage beyond the selected marginal position determined thereby, a shiftable member on the frame adapted to be engaged by the carriage in a final stop position of the carriage beyond its said selected 50 marginal position, and a connection between said shiftable member and said shiftable stop member for actuation of the latter to move said locking means to locking position as the carriage reaches its said final stop position.
18. Margin stop mechanism for a typewriter having a frame and a platen carriage thereon, which includes a bar member on said carriage, a margin block adjustably mounted on said bar member and having a stop abutment, a stop lever 55 mounted on said frame for longitudinal shift movement equal at least to one complete escapement movement of said carriage, said stop lever having a stop element on one end thereof adapted to be engaged by said stop abutment in one 60
- 75

5 marginal position of said carriage, escapement-movement-prevention means connected to the other end of said stop lever and actuated thereby, and means for adjusting said bar member longitudinally of said carriage to position said stop abutment to permit at least one complete escapement movement of said carriage after said stop abutment engages said stop element.

10 19. Margin stop mechanism for a typewriter having a frame and a platen carriage thereon, which includes a rack bar mounted on said carriage longitudinally thereof, a margin block mounted on said bar and having means adjustable to engage the teeth of said bar in different 15 positions of said block thereon, a stop lever mounted on said frame for longitudinal shift movement somewhat greater than one complete escapement movement of said carriage, a stop element on one end of said stop lever adapted to be engaged by said margin block when a marginal 20 position of said carriage is reached, locking means preventing escapement movement of said carriage connected to and actuated by the other end of said stop lever, and means for adjusting 25 said rack bar longitudinally of said carriage to so position said margin block relative to said stop element as to cause the former to engage the latter at such a time that the carriage can move substantially one complete escapement movement after engagement of said margin block with 30 said stop element.

20 20. Margin stop mechanism for typewriters having a frame and a platen carriage thereon, which includes a rack bar mounted on said car-

riage, a margin block mounted on said rack bar and having means selectively engageable with the teeth of said bar for holding said block in different positions along said bar, a stop abutment on said block, a stop member on said frame adapted to be engaged by said stop abutment in a marginal position of said carriage, and means for mounting said bar on said carriage including U-shaped supports receiving the opposite ends of said bar, said bar having slots in its opposite ends, members securing said U-shaped supports to said carriage and passing through said bar slots to prevent lateral displacement thereof, and adjustable members carriage by said U-shaped supports and engaging the opposite ends of said 15 bar for shifting the latter longitudinally relative to said U-shaped supports.

21. In margin stop mechanism for typewriters, a margin block and means for supporting said margin block which includes a rack bar upon 20 which said margin block is slidably supported, said margin block having means engaging the teeth of said rack bar to hold it in adjusted position on said rack bar, U-shaped supports receiving the opposite ends of said rack bar, said 25 rack bar having elongated slots in its opposite end portions, means adapted for securing said supports to a platen carriage and extending freely through said bar slots, adjusting screws carried by said supports and engaging the opposite 30 end edges of said bar.

DWIGHT P. ROWLAND.
CONRAD C. DAHL.
